Primary Examiner—Alan P. Douglas*Assistant Examiner*—Robin V. Taylor*Attorney, Agent, or Firm*—Dougherty & Associates[57] **CLAIM**

The ornamental design for a stackable container for dispensing fluid, as shown and described.

DESCRIPTION

FIG. 1 is a perspective view of a stackable container for dispensing fluid, showing my new design;

FIG. 2 is a left side elevational view of the stackable container of FIG. 1;

FIG. 3 is a top view thereof;

FIG. 4 is a front elevational view thereof;

FIG. 5 is a right elevational view thereof;

FIG. 6 is a rear side elevational view thereof;

FIG. 7 is a bottom view thereof;

FIG. 8 is a perspective view of an alternative embodiment of a stackable container for dispensing fluid, showing my new design;

FIG. 9 is a left side elevational view of the stackable container of FIG. 8;

FIG. 10 is a top view thereof;

FIG. 11 is a front elevational view thereof;

FIG. 12 is a right elevational view thereof;

FIG. 13 is a rear side elevational view thereof; and,

FIG. 14 is a bottom view thereof.

The broken line showing is for illustrative purposes only and forms no part of the claimed design.
